NUT-CRACKING MACHINE

Leo J. Meyer, St. Louis, Mo., assignor, by direct and mesne assignments, of one-third to John A. Schuler, St. Louis, Mo., and two-thirds to The Champion Pecan Machine Company, San Antonio, Tex., a corporation of Texas

Application October 21, 1935, Serial No. 45,875

4 Claims. (Cl. 146—12)

This invention relates generally to nut-cracking machines, and more particularly to a nut-cracking machine which is capable of cracking edible nuts of varying sizes in a simple and effective manner, without danger of mashing the kernels of the nuts, the predominant object of the invention being to provide an improved nut-cracking machine of this type which includes means arranged for continual rotary motion during operation of the machine which receives and supports the nuts during nut-cracking operations of the machine.

Fig. 1 is a side elevation of the improved nut-cracking machine.

Fig. 2 is an end elevation of the machine with parts thereof shown in section.

Fig. 3 is an elevation of the end of the machine opposite to the end illustrated in Fig. 2 and with parts of the machine shown in section.

Fig. 4 is a fragmentary sectional view taken longitudinally through the machine on line 4—4 of Fig. 2.

Fig. 5 is a fragmentary, sectional view taken on line 5—5 of Fig. 3, illustrating the means for conveying nuts from the hopper of the machine to the nut-cracking means thereof.

Fig. 6 is an enlarged fragmentary, sectional view of the compensating mechanism of the machine which serves to insure application of uniform nut-cracking force to nuts of varying sizes.

Fig. 7 is a fragmentary, enlarged view showing one of the nut-receiving elements associated with the endless chain of the nut-feeding mechanism of the machine.

Fig. 8 is a side elevation of the parts shown in Fig. 7.

In the drawings, wherein is shown for the purpose of illustration, merely, one embodiment of the invention, A designates the improved nut-cracking machine generally. The machine A includes a frame or bed 1 which is supported upon suitable legs 2, and this frame or bed supports the various parts of the machine which will be hereinafter described. Extended transversely of the bed of the machine A adjacent to an end thereof is a main shaft 3 which is mounted in bearings 4 (Fig. 2) that are supported by the bed of the machine, said main shaft having fixedly mounted thereon a gear wheel 5. The gear wheel 5 has arranged in mesh therewith a pinion 6 which is mounted on a shaft 7, said shaft 7 being supported for rotation in a bearing 8 extended transversely of the machine above the bed thereof. Also mounted on the shaft 7

is a pulley 9, over which a power transmission belt 10 operates, this belt operating also over a smaller pulley 11 mounted on the power shaft 12 of an electric motor 13. The electric motor 13 is supported by suitable bracket means 14, which in turn is secured to a structure 15 of which the bearing 8 forms a part, the structure 15 being secured to and extended upwardly from the bed 1 of the machine. It is obvious that rotary movement will be transmitted from the pulley 11 to the pulley 9 by the belt 10 so as to rotate the shaft 7 and thereby transmit rotary motion to the main shaft 3 of the machine through the pinion 6 and the gear wheel 5.

Fixedly mounted on the main shaft 3 of the machine A is a worm 16 (Figs. 1 and 2), with which a worm wheel 17 is arranged in mesh. The worm wheel 17 is mounted on a shaft 18 which extends longitudinally of the machine, said shaft 18 being mounted for rotation in bearings 19. At the end of the shaft 18 opposite to the end thereof at which the worm wheel 17 is arranged, a rotary nut-receiving member 20 is fixed to said shaft for rotary movement therewith. The rotary nut-receiving member comprises a body portion 21, which is fixed to the shaft 18 by means of a key 21' or otherwise, and an outer portion 22, which is secured to the body portion by bolts 23 which extend through circular apertures formed through the body portion 21 and arcuate slots 24 formed in the outer portion 22 so as to permit adjustment of the outer portion 22 about the shaft 18 and with respect to the body portion 21. The outer portion 22 of the nut-receiving member 20 includes outwardly extended and circumferentially spaced portions 25 (Fig. 3), each of which includes a nut-receiving pocket 26. It is important to note that the nut-receiving pockets 26 are not parallel with respect to the axis of the shaft 18, but instead said pockets are extended longitudinally at a slight angle relative to the axis of said shaft 18. This is shown most clearly in Figs. 1, 3, and 4.

The improved nut-cracking machine includes a hopper which receives nuts to be cracked by the machine, said hopper including a tapered upper portion 27 which communicates with a lower hopper portion 28 which has an inclined lower wall 28', and this lower hopper portion 28 communicates in turn with a hopper portion 29 arranged at one side of the lower hopper portion 28. By referring particularly to Figs. 1 and 5, it will be noted that the hopper portion 29 is provided with an inclined wall 29' which merges into a curved portion 30 which is open at its

outer end. Also, the views mentioned show that the hopper portion 29 is provided with an upwardly inclined end wall 31, which is provided at its top with a horizontal portion 31^a and at 5 its bottom with a portion 31^b which is extended at a slight angle with respect to said end wall. An endless conveyor 32 is arranged at the end wall 31 of the hopper portion 29, said endless conveyor comprising upper and lower sprocket 10 wheels 33, over which operates a sprocket chain 34 which is provided with spaced nut-receiving elements 35. It is to be noted that one flight of the endless sprocket chain 34 of the conveyor 32 moves upwardly within the hopper portion 29 in 15 contact with the inner face of the end wall 31 thereof, and that the other flight of said endless chain moves downwardly in a position outside of said hopper portion (see Fig. 5). The upper sprocket wheel 33 of the endless conveyor is 20 mounted on a shaft 33^a which is supported in bearings mounted on the horizontal portion 31^a of the end wall of the hopper portion 29, and the lower sprocket wheel 33 of said conveyor is mounted on a shaft 33^b which is supported in 25 bearings fixed to the bed of the machine. The chain 34 of the conveyor 32 receives its movement through the instrumentality of a sprocket chain 34^a which operates over sprocket wheels 34^b and 34^c mounted on the shafts 3 and 33^b, 30 respectively (Fig. 1).

Each of the nut-receiving elements 35 comprises a pair of spaced, plate-like elements 36 shaped in side elevation as shown to the best advantage in Fig. 8, and the pair of associated 35 plates providing each nut-receiving element constitutes a link in the endless chain 32, being connected to adjacent links of the chain by the usual pins or rivets. The pair of plates 36 providing each nut-receiving element include extended portions 37, which project outwardly beyond the chain proper, and at the tops and bottoms of these extended plate portions outwardly flared portions 37' are provided. These outwardly flared portions 37' provide nut-receiving pockets. 40 As is apparent in Fig. 7, the nut-receiving pocket at the top of the nut-receiving element is larger than the nut-receiving pocket at the bottom thereof. Thus when larger nuts are being cracked by the machine the chain 34 will be arranged so that the larger nut-receiving pockets are uppermost as the nut-receiving elements 35 45 pass upwardly through the hopper, and when smaller nuts are being cracked the chain will be arranged so that the smaller nut-receiving pockets are the uppermost, effective nut-receiving 50 pockets.

The rotary nut-receiving member 20 is disposed within a housing 40 which includes an upper, inclined wall 41 and a lower, discharge chute 42. 60 In the operation of the machine, the uppermost-nut-receiving pocket of each nut-receiving element 35 picks up a nut as said nut-receiving element passes upwardly through the hopper, wherein a store of nuts is maintained. As each nut-receiving element 37 passes over the upper sprocket wheel 33, the nut is discharged therefrom onto the inclined wall 41, said nut sliding down said wall into the main portion of the housing 40 of the rotary nut-receiving member 20, 65 where said nut is received by a pocket 26 of said nut-receiving member. The nut-receiving member 20 is constantly rotated during operation of the machine, and the nut so deposited in a pocket thereof is carried around by the nut-receiving member, said nut being cracked during its travel 70

75 with the nut-receiving member in a manner to be hereinafter explained, and being thereafter discharged in a cracked condition from the chute 42. It will be noted that the curved portion 30 at the bottom of the hopper 29 is provided with an extension 43 (Fig. 5). This extension prevents the nuts from falling from the open lower end of the hopper, and the plates 36 of the nut-receiving elements 35 straddle said extensions when passing same, or pass at opposite sides thereof. 10

The improved nut-cracking machine disclosed herein includes a compensating mechanism which provides for the same cracking pressure being applied to various nuts, even though they are of different sizes. This mechanism is best shown 15 in Figs. 4 and 6, wherein the compensating mechanism is designated by the reference character 45. The compensating mechanism comprises a movable die 46, which is movable toward and from a fixed die 47, said fixed die being supported by 20 a portion 48 associated with the bed of the machine. The dies 46 and 47 are provided with cavities 49 formed in their nut-contacting faces.

The movable die 46 is associated with a rack 50 which is guided for reciprocatory movement within 25 a carriage or box-like structure 51, this box-like structure comprising a body portion 52 and a cover plate 53. By referring to Fig. 4 it will be noted that the bottom wall of the body portion 52 of the box-like structure 51 is thicker at its 30 forward end than at its rearward end, a shoulder 54 being present at the point where the thicker and thinner portions of said bottom wall meet. Mounted for reciprocating movement within the rear portion of the box-like structure 51 is an element 55 which is provided with a wall portion 56, which extends to the lower face of the cover plate 53 of said box-like structure. A pin 57 extends forwardly from said wall portion into a cavity 58 formed in the body portion of the rack 50, 40 and a coil spring 59 which encircles said pin contacts at its opposite ends with the forward face of the wall portion 56 and the face at the inner end of the cavity 58 formed in the rack 50. This coil spring tends to move the rack 50 and the associated die 46 in a forward direction, a plate 60 which is secured to the forward face of the body portion 52 of the box-like structure 51 serving as a stop with which a shoulder 50' at the forward end of the rack contacts to limit forward 50 movement of the rack and die 46 with respect to the box-like structure 51, in response to pressure of the coil spring 59.

Mounted on a shaft 61 supported by the bottom wall and cover plate of the box-like structure is 55 a pinion 62 which meshes with the teeth of the rack 50, this pinion having associated with it a disk 63 which is provided with a toothed or roughened peripheral surface. The pinion and the disk rotates as a unit, and the element 55 is provided 60 with a curved face 64 having a toothed or roughened face. Also the element 55 is connected to a disk 65 mounted on the main shaft 3 of the machine by a link 66, which is pivotally attached at 67 to the disk 65 and at 68 to the element 55 (Fig. 65 4). The element 55 has extended downwardly from the bottom wall thereof a lug 69 which passes through an elongated opening 70 formed in the bottom wall of the box-like structure 51. This lug is engaged by an end of a plunger 71 supported by the portion 72 associated with the bottom wall of the box-like structure, and said plunger 71 is urged toward said lug by a coil spring 73 housed within said portion 72.

The forward portion of the bed of the machine 75

supports a screw-threaded element 74 (Fig. 6), which is alined longitudinally of the machine with an opening 75 formed in the body portion of the box-like structure 51 and with an opening 76 of smaller diameter which is formed in the plate 60. Arranged within the opening 75 is a disk 77 from which a pin 78 is extended, said disk being engaged by one end of a coil spring 79 which contacts at its opposite end with the inner 10 end wall of the opening 75. The coil spring 79 surrounds the pin 78 and said coil spring forces the disk 77 into close contact with the portion of the inner face of the plate 60 which surrounds the opening 76 formed therein.

15 In the operation of the machine, the nuts to be cracked are carried around in the pockets 26 of the constantly rotating element 20 in the direction of the arrow in Fig. 3 to the position C of the dies 46 and 47. As each pocket 26 of the 20 element 20 approaches the cracking position C, the machine is so timed that the compensating mechanism 45 moves forwardly as a unit until the forward end of the movable die 46 contacts with the nut carried within the pocket and moves 25 said nut into contact also with the fixed die 47, the inclined arrangement of the pockets permitting the die 46 to move into said pockets while the member 20 is rotating. The position of the nut between the dies 46 and 47 arrests further 30 forward movement of the movable die 46, but the box-like structure 51 and the element 55 continue their forward movement in response to rotary movement of the disk 65. During such forward movement of the box-like structure 51 and the 35 element 55 with respect to the rack 50 the coil spring 59 is compressed, and also because the pinion 62 is moved longitudinally of the teeth of the rack this pinion and the disk 63 associated therewith are rotated. When the box-like structure 40 has moved the proper distance in a forward direction, the end portion of the screw-threaded element 74 (Fig. 6) will enter the opening 76 in the plate 60 to contact with the disk 77, whereby the coil spring 79 will arrest further forward 45 movement of the box-like structure.

At this time the element 55 has not quite reached the forward limit of its movement, and therefore said element 55 continues to move forwardly. This additional movement brings the 50 toothed face 64 into contact with the toothed peripheral face of the disk 63 so as to arrest further rotation of the pinion 62 and lock the pinion and the rack together, so that they are incapable of further relative movement. This happens just 55 before the element 55 reaches the limit of its forward movement, and as said element 55 continues its forward movement after contact of the face 64 with the peripheral face of the disk 63, the element 55, the box-like structure, and the rack 60 50 and die 46 are locked together, and all of said parts move forwardly as a unit. This additional movement gives to the die 46 the necessary forward movement to crack the nut without crushing the kernel thereof. It is to be observed that 65 while forward movement of the box-like structure 51 is arrested by the screw-threaded element 74, the coil spring 79 permits said box-like structure to move forwardly the required additional distance to crack the nut.

70 When the nut has been cracked as described, the compensating mechanism 45 is moved rearwardly in response to movement of the disk 65 and the link 66, and at this time the coil spring 73 separates the face 64 from the peripheral face 75 of the disk 63. The nut-carrying element 20 dur-

ing this time is rotating, and eventually the compensating mechanism will again move forwardly to enable the die 46 to engage the nut in the next pocket of the element 20 as it approaches the cracking position C, the compensating operation 5 and the cracking operation being performed as each successive pocket of the element 20 approaches and reaches the nut-cracking position.

The extensions 25 of the nut-receiving member 20 at their opposite sides are provided with recesses 80 and 81, the recesses at each side of said member being arranged in circular formation concentric with respect to the shaft 18. The opposite walls of the housing 40 of the member 20 are provided with curved extensions 82 and 83, 15 which are received by the recesses 80 and 81 as the member 20 rotates. These curved extensions serve to guide the nuts to their proper positions in the pockets 26 of the member 20, and also said extensions act to dislodge any nuts which may 20 become jammed in said pockets. If desired, the extension 82 may be provided with a toothed or serrated edge which causes the nuts to be agitated, so that positioning of the nuts will be 25 aided and sticking thereof prevented. It will be noted that the extension 83 is provided with an inclined face 83', which serves to cam the nuts to the centers of the pockets as the nut-receiving member rotates with respect to said extension. Also the portions 25 of the nut-receiving member 30 20 are provided with depressions 25' which aid in centering the nuts in the pockets.

It is important to note that when a nut is engaged between the cracking dies of the machine, its movement with the constantly rotating nut-receiving member 20 is arrested, and the pocket of said nut-receiving member in which the nut was carried moves away from the arrested nut. Thus, when the actual cracking of the nut takes place, it is entirely spaced apart from the pocket 35 of the nut-receiving member in which it was carried to the cracking position, and therefore the nut is free from contact with any parts of the machine which might tend to interfere with complete cracking of the shell of the nut. 40 45

I claim:

1. A nut-cracking machine comprising a substantially circular member mounted for rotary movement and provided with nut-receiving pockets spaced circumferentially thereof, said nut-receiving pockets being open at their opposite ends at opposite sides of said member and each pocket being open longitudinally of its length at a side thereof to permit introduction of nuts into said pocket, means for imparting constant rotary 50 movement to said member, means for delivering nuts to the pockets of said member, and nut-cracking means for cracking nuts carried by the pockets of said member, said nut-cracking means including a pair of alined and spaced apart cracking elements between which the pocketed circumferential portion of said member rotates, and means for subjecting one of said cracking elements to reciprocatory movement toward and from the associated cracking element and into 55 and out of the pockets of said member as said pockets successively move into operative position with respect to said cracking elements and while said pockets are in movement so as to crack between said cracking elements the nuts carried 60 by said pockets, the axis of each pocket being extended at an angle with respect to the axis of said reciprocating cracking element when each pocket is in cooperative relation with respect to 65 said reciprocating cracking element so as to per- 70 75

mit said reciprocatory cracking element to move into the pocket while said member of which the pocket forms a part is in constant rotary motion.

2. A nut-cracking machine comprising a substantially circular member mounted for rotary movement and provided with nut-receiving pockets spaced circumferentially thereof, said nut-receiving pockets being open at their opposite ends at opposite sides of said member and each pocket being open longitudinally of its length at a side thereof to permit introduction of nuts into said pockets, means for imparting constant rotary movement to said member, means for delivering nuts to the pockets of said member, nut-cracking means for cracking nuts carried by the pockets of said member, said nut-cracking means including a pair of aligned and spaced apart cracking elements between which the pocketed circumferential portion of said member rotates, and means for subjecting one of said cracking elements to reciprocatory movement toward and from the associated cracking element and into and out of the pockets of said member as said pockets successively move into operative position with respect to said cracking elements and while said pockets are in movement so as to crack between said cracking elements the nuts carried by said pockets, and means for dislodging nuts from the pockets of said member after said nuts have been cracked.

3. A nut-cracking machine comprising a substantially circular member mounted for rotary movement and provided with nut-receiving pockets spaced circumferentially thereof, said nut-receiving pockets being open at their opposite ends at opposite sides of said member and each pocket being open longitudinally of its length at a side thereof to permit introduction of nuts into said pockets, means for imparting constant rotary movement to said member, means for delivering nuts to the pockets of said member, and nut-cracking means for cracking nuts carried by the pockets of said member, said nut-cracking means including a pair of aligned and spaced apart cracking elements between which the pocketed circumferential portion of said member rotates, one of said cracking elements being fixed in a stationary position and the other of said cracking elements being supported for reciprocatory movement, means for subjecting said reciprocatory cracking element to reciprocatory movement toward and from the stationary cracking element and into and out of the pockets of said member as said pockets successively move into operative position with respect to said cracking elements and while said pockets are in movement so as to crack between said cracking elements the nuts

carried by said pockets, the axis of each pocket being extended at an angle with respect to the axis of said reciprocatory cracking element when each pocket is in cooperative relation with respect to said reciprocatory cracking element so as to permit said reciprocatory cracking element to move into the pocket while said member of which the pocket forms a part is in constant motion, and means cooperatively associated with said reciprocatory cracking element for compensating for nuts of different lengths so that a fixed amount of cracking movement is applied to each nut being cracked regardless of the length of the nut.

4. A nut-cracking machine comprising a substantially circular member mounted for rotary movement and provided with nut-receiving pockets spaced circumferentially thereof, said nut-receiving pockets being open at their opposite ends at opposite sides of said member and each pocket being open longitudinally of its length at a side thereof to permit introduction of nuts into said pockets, means for imparting constant rotary movement to said member, means for delivering nuts to the pockets of said member, and nut-cracking means for cracking nuts carried by the pockets of said member, said nut-cracking means including a pair of aligned and spaced apart cracking elements between which the pocketed circumferential portion of said member rotates, one of said cracking elements being fixed in a stationary position and the other of said cracking elements being supported for reciprocatory movement, means for subjecting said reciprocatory cracking element to reciprocatory movement toward and from the stationary cracking element and into and out of the pockets of said member as said pockets successively move into operative position with respect to said cracking elements and while said pockets are in movement so as to crack between said cracking elements the nuts carried by said pockets, the axis of each pocket being extended at an angle with respect to the axis of said reciprocatory cracking element when each pocket is in cooperative relation with respect to said reciprocatory cracking element so as to permit said reciprocatory cracking element to move into the pocket while said member of which the pocket forms a part is in constant motion, means cooperatively associated with said reciprocatory cracking element for compensating for nuts of different lengths so that a fixed amount of cracking movement is applied to each nut being cracked regardless of the length of the nut, and means for dislodging nuts from the pockets of said member after said nuts have been cracked.

LEO J. MEYER.
